UNITED STATES PATENT OFFICE.

WILLIAM BELFIELD, ROBERT SHEARER, JOHN FINDLAY, GAMALIEL BELFIELD, AND GEORGE GLEASON, OF MINOOKA, ILLINOIS.

LOCK-NUT FOR VEHICLE-AXLES.

SPECIFICATION forming part of Letters Patent No. 781,803, dated February 7, 1905.

Application filed March 9, 1904. Serial No. 197,290.

To all whom it may concern:

Be it known that we, WILLIAM BELFIELD, ROBERT SHEARER, JOHN FINDLAY, GAMALIEL BELFIELD, and GEORGE GLEASON, citizens of the United States, residing at Minooka, in the county of Grundy and State of Illinois, have invented a new and useful Improvement in Lock-Nuts for Vehicle-Axles, of which the following is a specification.

Our invention relates to lock-nuts for vehicle-axles; and our object is to provide a construction better adapted to attain the result desired than is shown in the invention embodied in Letters Patent of the United States No. 710,240, of September 30, 1902, granted to William Belfield, Robert Shearer, John Findlay, and Gamaliel Belfield, the same being more particularly described hereinafter and illustrated in the accompanying drawings, in which—

Figure 1 is a perspective view of the end of an axle-spindle, showing oppositely-disposed lateral lugs in which are recesses adapted to receive lugs projecting from the interior wall 5 of the nut, as hereinafter described. Fig. 2 is a front elevation of the nut, showing a lock-lever pivotally mounted therein and flush with the outer face thereof. Fig. 3 is a rear elevation of the nut, showing the inner projecting end of the lock-lever in proper position and also the rear ends of two inwardly-projecting lugs which are formed for beveled abutments for holding the nut from sliding longitudinally of the axle-spindle when the lugs are turned into engagement with the recesses of the lugs thereon. Fig. 4 is a cross-section of the nut on broken line A B, Fig. 2, looking in the direction indicated by arrow C to illustrate the lock-lever in proper position, together with one of the beveled abutments above referred to. Fig. 5 is a plan of the outer end portion of an axle-spindle with the end broken away to the same cross-section as the nut mounted thereon, which latter is shown in the same section as in Fig. 4 to illustrate manner of locking the nut.

Like numerals indicate like parts throughout the several views.

The axle-spindle 1 is provided with a tenon

portion at the extreme outer end, and integral therewith are two oppositely-disposed lugs 2 and 3. In each of these lugs is formed a recess, as at 4, the rear face 5 thereof being to an angle less than a right angle to the longitudinal center of the spindle. There is a hole through the nut, and at opposite sides thereof project lugs, such as 6, which have inclined end surfaces, as shown in Fig. 4 at 7, which are adapted to be turned, with the nut, into the recesses 4 and on account of close contact with the inclined faces 5 hold the nut from outward movement.

The outer ends of the lugs 2 and 3 terminate at a distance from the tip of the axle and are each inclined or beveled so that it tapers gradually and unites with the surface of the spindle with a feather-edge, and the bore or opening through the nut also tapers to correspond with the exterior of said lugs, so that it is substantially bell-shaped in longitudinal cross-section, as shown in Figs. 4 and 5. This construction permits of the nut being easily and quickly placed upon the end of the spindle, as the flaring end of the bell is much larger than the end of the spindle and there are no sharp angles or abrupt corners or shoulders to interfere with each other and require a partial rotation of the nut. It also causes a slight inward movement of the nut on the axle to a greater or less extent, caused by the engagement of the faces 5 and 7, which are straight from end to end and slightly inclined or located at an angle to the axis of the spindle, so that they have a tendency to tighten the nut by the coöperation of the longitudinal bell shape of the nut and axle and the circumferential wedge action of the inclined faces of the shoulders and lugs.

At 8 is a notch in the outer end of the tenon of the axle-spindle, and at 9 is pivotally mounted in the nut a lock-lever 10, whose inner end is fitted and so relatively disposed that it will engage in the notch 8 when the nut is in position, with inclined lugs disposed in the recesses of the axle-spindle, and thus lock the nut from turning to the open position. The lever is held in its normal or operative position by a spring 11, which is seated

in a longitudinal recess in the nut. It is preferably located in one corner of the nut, so that the pin on which it is pivoted can extend transversely across the corner from one surface to the other, as shown in Fig. 2. It is obvious that by pressing the outer end of the lever until it is in the position indicated by the broken lines in Fig. 5, when it is clear of the notch, the nut will be free to be turned to the position where it may be removed by being slid longitudinally from the spindle.

We claim as our invention—

In a lock-nut for vehicles, the combination, with an axle-spindle, the outer end of which is provided with a notch and with oppositely-located lugs, each lug having a lateral recess therein and terminating at a distance from the tip of the spindle being beveled or inclined at its outer end and joining the surface of the spindle with a feather-edge, of a nut on the spindle having a longitudinal recess in one corner, the bore of the nut being substantially bell-shaped in longitudinal cross-section to correspond with the exterior of the lugs on

the spindle and having oppositely-located lugs 25 to slide between the lugs of the spindle and be turned with the nut into the recesses thereof, the coöperative contacting faces of said lugs and recesses being straight from end to end and inclined at an angle to the axis of the 30 spindle, a lever pivotally mounted in the nut, the inner end of which is in position to enter the notch in the spindle and the outer end overhangs the recess, and a spring in the recess in engagement with the outer end of the 35 lever to hold the inner end in the notch in the end of the spindle.

In testimony whereof we have signed our names in the presence of witnesses.

WILLIAM BELFIELD.
ROBERT SHEARER.
JOHN FINDLAY.
GAMALIEL BELFIELD.
GEORGE GLEASON.
